UNITED STATES PATENT OFFICE

93,277

DESIGN FOR A MIRRORED DISPLAY STAND

Samuel Lapin and Benjamin M. Korn,
New York, N. Y.

Application June 15, 1934, Serial No. 52,193

Term of patent 3½ years

To all whom it may concern:

Be it known that SAMUEL LAPIN and BENJAMIN M. KORN, citizens of the United States and residents of New York in the county of New York and State of New York, have invented a new, original, and ornamental Design for a Mirrored Display Stand, of which the following is a specification, reference being had to the accompanying drawing, forming a part thereof.

The figure is a perspective view of the device, showing our design.

We claim:

The ornamental design for a mirrored display stand as shown.

In testimony whereof we have signed our names to the specification.

SAMUEL LAPIN.
BENJAMIN M. KORN.
